UNITED STATES PATENT OFFICE.

JOHN I. KELLEY, OF MOUNT UNION, PENNSYLVANIA.

ORNAMENT FOR MOTOMETERS.

Application filed August 2, 1924. Serial No. 729,733.

To all whom it may concern:

Be it known that I, JOHN I. KELLEY, a citizen of the United States, residing at Mount Union, in the county of Huntingdon and State of Pennsylvania, have invented certain new and useful Improvements in Ornaments for Motometers, of which the following is a specification, reference being had to the accompanying drawings.

10 This invention relates to ornaments for automobiles, and particularly to an ornamental device for motometers.

15 The object of the invention is to provide an ornamental device capable of being attached to motometers which, when in place at night, will be illuminated and assist in illuminating the thermometer of the motometer so as to show its position.

20 A further object is to so construct the device that light will be discharged from the central barrel of the device radially outward against the faces of two wings simulating flags against the under side of an eagle or other figure which is mounted upon the barrel.

25 My invention is illustrated in the accompanying drawing, wherein:—

30 Figure 1 is a perspective view of an ornament for motometers constructed in accordance with my invention;

35 Figure 2 is a vertical sectional view of the ornament;

Figure 3 is a section on the line 3—3 of Figure 2.

40 Referring to this drawing, 10 designates a cylinder of thin sheet metal, one end, being flanged, as at 11, and being annular to provide a central opening 12. The other end of the barrel is formed by a plate 14 having a central opening 14^a coinciding with the central opening 12 and having perforations 13 for the passage of screws whereby the barrel is held to the motometer A. This plate 14 is attached to the barrel in any suitable manner and formed to provide laterally projecting wings 15, one or both sides of which are painted to simulate flags as, for instance, the United States flag, these flags being preferably brought around approximately concentrically to the axial center of the barrel. Mounted upon the barrel between the flags and supported in any suitable manner is a figure 16 which will preferably have the form of an eagle with outstretched wings.

45 The barrel is formed in its lower portion

50 with an opening 17 disposed slightly to one side of a line cutting vertically downward through the center of the barrel and intended to accommodate the base of an electric light 18 of a small voltage. The barrel at opposite points is formed with circumferentially extending slots 19 which are disposed so as to throw the light radially outward against the front faces of the wings 15 55 and thus illuminate the flags. The barrel is also formed with a slot 20 which is disposed beneath the eagle and whereby the light will be thrown upward against the under side of the eagle and the eagle will, 60 therefore, be illuminated. Thus when the lamp 18 is energized at night, both flags and the eagle will be illuminated and a very attractive ornament will be provided for the automobile.

65 The barrel 10 is attached to the motometer A by screws *a* which pass through the openings 13, these screws being those which act to hold the sections of the motometer together. However, it is to be understood that this device might be attached to the motometer in any other suitable manner. The lamp 18, it will be seen, is disposed sufficiently to one side of the axial center of the barrel or tube 10 that this light does not interfere with the reading of the motometer but, on the contrary, illuminates the dial of the motometer so that it may be readily observed from the driver's seat. Preferably the forward end of the barrel, that is the end remote from its point of attachment to the motometer, will be closed by a pane of glass 21, though this pane might be made of celluloid. Preferably the pane will be of a yellow tone so that the light will not be 75 blinding.

80 I do not wish to be limited to placing the lamp 18 in any particular circuit, but preferably the lamp will be of low voltage, depending upon the equipment of the car. I 85 do not wish to be limited to any particular means of connecting the barrel to the flange 11 or to the plate 14, but preferably the barrel will be formed with longitudinally extending tabs 22 inserted through slots in the 90 plate and flange respectively and turned downward against the plate and flange, as illustrated.

95 I claim:—

An ornament for motometers comprising a 100 cylindrical barrel formed at one end with an attaching flange perforated for the pas-

sage of screws of the motometer casing, the flanged end of the barrel being provided with laterally projecting ornamental wings disposed approximately in the plane of said flange, and a figure mounted upon said flange of the barrel between the wings, the barrel having openings discharging light against the wings and against said figure, and an electric lamp disposed in the barrel

to one side of the middle thereof whereby it 10 will not obstruct the view of the indicating column of the motometer, the end of the barrel remote from said attaching flange being provided with a glazed opening.

In testimony whereof I hereunto affix my 15 signature.

JOHN I. KELLEY.
